[57] CLAIM

The ornamental design for a hose protector for a vehicle crossmember, as shown and described.

DESCRIPTION

FIG. 1 is a perspective view of our hose protector for a vehicle crossmember;

FIG. 2 is a top view thereof;

FIG. 3 is a front view thereof;

FIG. 4 is a bottom view thereof;

FIG. 5 is a back view thereof;

FIG. 6 is a right side view thereof;

FIG. 7 is a left side view thereof; and,

FIG. 8 is a reduced perspective view showing two of our hose protector for a vehicle crossmember in the environment in which they can be used.

The broken line showing of a partial vehicle frame and second hose protector, in FIG. 8, is for illustrative purposes only and forms no part of the claimed design.
